GIRDLE PAD

Victor Milstein, New York, N. Y.

Application October 14, 1949, Serial No. 121,255

1 Claim. (Cl. 2-2)

1 The present invention relates to attachments for wearing apparel, and more particularly, to a device for preventing the end of a rib in a garment from pressing into the body of the wearer including an element for attaching a protective pad to the garment.

Garments, such as girdles and the like worn for the purpose of improving the figure of the wearer, usually have a plurality of lengthwise extending ribs or stays, the ends of which terminate adjacent a marginal edge of the garment and tend to press into the body of the wearer by reason of the figure conforming shape of the garment. The pressing of the ends of the stays into the body is very annoying and in cases where the garment is worn for a long period without removal, the skin is irritated, chafed, or bruised. While in most garments some attempt is made to protect the body of the wearer by enclosing or lightly padding the ends of the ribs, this has not been found to be sufficient.

Accordingly, an object of the present invention is to provide a simple, practical and inexpensive device for overcoming the foregoing difficulties by preventing the ribs in the garment from pressing into the body of the wearer.

Another object is to provide a device of the foregoing character which is readily positioned on the garment and removed therefrom but is effectively retained on the garment against accidental removal.

A further object is to provide an element which can be produced at a very low cost and is very effective in attaching the device to the garment.

Other and further objects will be obvious upon an understanding of the illustrative embodiment about to be described, or will be indicated in the appended claims, and various advantages not referred to herein will occur to one skilled in the art upon employment of the invention in practice.

In accordance with the invention, the foregoing objects are accomplished by providing a device of the character indicated herein which comprises a pad, and an element secured to the pad having means, such as hook portions, for supporting the pad on the garment and positioning the pad between the end of the rib of the garment and the body of the wearer. In an embodiment of the invention about to be described, the element is formed with means, such as teeth, for gripping the garment to prevent the supporting means from being rendered ineffective.

A preferred embodiment of the invention has been chosen for purposes of illustration and de-

scription and is shown in the accompanying drawing, forming a part of the specification, wherein:

Figure 1 is a fragmentary perspective view illustrating a device embodying the present invention attached to a ribbed garment and positioned between the upper end of a rib and the body of the wearer of the garment.

Figure 2 is an enlarged front elevational view 10 of the device shown in Figure 1.

Figure 3 is an enlarged perspective view of the element for attaching the device to the garment.

Figure 4 is a sectional view taken along the line 4-4 on Figure 2 but showing the device 15 attached to the garment as illustrated in Figure 1.

Referring to the drawing in detail and more particularly to Figure 1 thereof, there is shown a garment 10, such as a girdle having a lengthwise extending rib 11 therein, the upper end of 20 which terminates adjacent the upper marginal edge 12 of the garment, and a device 14 attached to the garment at the upper edge thereof and positioned between the upper end of the rib and the body of the wearer of the garment to prevent the rib from pressing into the body.

The device 14, as shown in Figures 2, 3, and 4, comprises a relatively thin flat pad 15 of suitable shape and size to underlie the upper end of the rib, and a clip element 16 secured to one 30 face of the pad, for example by stitching 17.

The pad 15 may be constructed in any suitable manner, for example, by enclosing a padding strip 19 (Figure 4) of soft or resilient material, such as air-foam rubber, felt or the like, in an envelope or casing 20 of fabric.

The clip element 16, as shown in Figures 2 and 3, is a thin, flat, somewhat elongate strip formed of sheet metal, plastic, or other material which lends itself to simple and economical fabrication 40 and which facilitates slight bending to enable the element to conform to the curvature of the body of the wearer of the garment to which the device is attached.

The element comprises a pair of spaced apart 45 hook-shaped portions 21 each adjacent one end of the element at the upper edge thereof and extending forwardly of the element with outwardly turned ends 23 to facilitate disposition on a garment, a plurality of teeth or serrations 22 at the upper edge intermediate the hook-shaped portions, an elongate slit or aperture 24, and a row of teeth or serrations 25 defining the upper edge of the slit 24.

As shown in Figures 2 and 4, the slit 24 provides a bar portion 26 about which the stitching

is applied to secure the element 16 to the pad 15. Preferably, the element is positioned on the pad, so that the upper portion of the pad extends upwardly beyond the hook-shaped portions 21. In this manner, when the device is supported on the upper or marginal edge 12 of the garment with the hooks straddling the rib 11 (Figure 1), the pad extends above the upper end of the rib between the garment and the body of the wearer and prevents the rib from pressing into the body.

In order to prevent the device, when positioned as shown in Figures 1 and 4, from creeping or working its way upwardly and becoming detached because of movement of the wearer, the teeth 22 and 25 are bent or extend forwardly out of the plane of the element, so that they bite into the underside of the garment (Figure 4) to retain the hooks in supporting relation on the edge 12 of the garment. It is to be noted that the outwardly bent ends 23 of the hooks extend downwardly to a point opposite the upper teeth 22. This is done to provide an abutment whereby the cloth will be more readily engaged by the teeth 22 and thus further prevent dislocation of the pad from the garment; as it has been found that, when the ends 23 terminate above the teeth 22, the hooks tend to become dislodged from the garment.

While a single element 16 has been illustrated attached to the pad 15, it will be appreciated that a pair of such elements about half as long as the element shown and having a single hook could be utilized to thereby give the device greater flexibility for adjusting itself to the curvature of the wearer's body.

From the foregoing description, it will be seen that the present invention provides a simple, practical, and inexpensive device for preventing the ribs of garments from pressing into the body of the wearer. The devices are readily attached and removed but when assembled cannot be displaced accidentally. The attaching element is

extremely simple and practical in construction, can be made at a very low cost and is readily sewn to the pad. The device is sanitary since it adapts itself to washing or dry cleaning without impairment of the parts thereof.

As various changes may be made in the form, construction and arrangement of the parts herein, without departing from the spirit and scope of the invention and without sacrificing any of its advantages, it is to be understood that all matters are to be interpreted as illustrative and not in any limiting sense.

What is claimed is:

A device for preventing the end of a rib in a garment from pressing into the body of the wearer comprising a substantially thin flat pad, and an elongate member secured to said pad on one side thereof adapted to face the underside of the garment, said element having a hook-shaped portion adjacent each end thereof for engaging a marginal edge of the garment to support said pad thereon and having a serrated edge intermediate said portions and extending outwardly from said pad for engaging the underside of the garment for preventing relative movement between said pad and the garment, said serrated edge being substantially in alignment with ends of said hooked shaped portions.

VICTOR MILSTEIN.
